UNITED STATES PATENT OFFICE.

FRANK J. WATERS, OF PROVIDENCE, RHODE ISLAND, ASSIGNOR TO WATERS ENGINE COMPANY, OF SACO, MAINE, A CORPORATION OF MAINE.

ROTARY STEAM-ENGINE.

No. 926,914.

Specification of Letters Patent.

Patented July 6, 1909.

Application filed August 17, 1907. Serial No. 389,057.

To all whom it may concern:

Be it known that I, FRANK J. WATERS, a citizen of the United States, residing at Providence, in the county of Providence and 5 State of Rhode Island, have invented certain new and useful Improvements in Rotary Steam-Engines, of which the following is a specification, reference being had therein to the accompanying drawings.

10 Like reference numerals indicate like parts.

Figure 1 is a view in elevation of the piston and piston case of my improved rotary steam engine, in position in said cylinder, the cylinder being shown in longitudinal section, as 15 seen on line *y y* of Fig. 8. Fig. 2 is a view of said cylinder, piston, and piston case and associated parts, as seen in section on line *y y* of Fig. 8. Figs. 3, 4, 5 and 6 are detail views. Fig. 7 is a sectional view of the 20 piston, piston parts and a portion of the cylinder, as seen on line *z z* of Fig. 2. Fig. 8 is a cross sectional view of the cylinder, ports, piston and piston parts, as seen on line *v v* of Fig. 2, the piston and piston parts 25 being shown in horizontal position. Fig. 9 is a similar view with the piston and piston parts, seen in vertical position. Fig. 10 is a detail sectional view of the piston valve structure, as seen on line *W W* of Fig. 2.

30 Fig. 11 is a detail view.

My invention relates to rotary steam engines, and consists of the novel construction, arrangement and combination of the several parts as hereinafter described and claimed.

35 The purpose of my invention is to simplify the construction and operation of rotary steam engines. In my improved rotary steam engine, there is only one sliding blade or piston in the piston case, and this is 40 always of the same length; and of invariable dimensions, the inner surface of the cylinder itself presses the single piston or blade inwardly by the contact of the ends of said piston or blade with said surface of the cylinder bore, said bore being formed in a series 45 of eccentric, consecutive, concave, continuous curvatures, which permit and cause such cam-like action. The cylinder of my said rotary engine, as seen in cross section and 50 illustrated in Figs. 8 and 9 may be defined as a cylinder having a bore whose peripheral walls are equally distanced from each other on every line passing through a single point which is exterior to the geometrical center of 55 said bore. A machine for automatically

forming this peculiarly shaped bore in a cylinder is shown in my pending application for Letters Patent, Serial No. 389,058, filed herewith.

The cylinder 1 has the annular flanges 2 at its ends, shown in Figs. 1 and 2. At each end of the cylinder 1 is a cylinder head 3, having an annular flange 4. The flanges 3 and 4 are fastened together by bolts 5. The cylinder 1 has a base 6, provided with flanges 65 7, as seen in Figs. 8 and 9. A steam inlet port 8 and a steam outlet port 9 are made through the base 6, and a steam passage-way 10, 11, extends between the ports 8 and 9. An upward extension 12 of the main 70 valve seat (not shown) has flanges 13. Bolts 14 fasten the flanges 7 and 13 together. A steam inlet port 15 in said extension 12 is continuous with the port 8, and a steam outlet port 16 in the extension 12 is continuous 75 with the port 9. Each cylinder head 3 has a concentric tubular part or sleeve 17, integral therewith, to furnish a bearing for the piston case 18 and the hubs 19 and the main shaft 20 thereof. A tubular gland 21 has a 80 flange which is secured by bolts 22 to the outer edge of each sleeve 17, and presses a packing 23 to insure a steam tight fit of the main shaft 20 in the sleeve 17, said sleeve at its outer end having its bore enlarged for 85 that purpose, as seen at 24, in Fig. 2.

The piston case 18 is most plainly shown in Figs. 1 and 7. The cylindrical body of the piston case, the hubs 19 and the main shaft 20 are preferably integral, and are continuous 90 in one axial line. A fly-wheel and a driving pulley, (not shown) are mounted on the main shaft. The cylindrical body of the piston case has a central rectangular slot through it. In this slot are placed the two 95 guide plates 25, which are secured by screws 26 to the body of the piston case 18 and rotate with it. The piston or blade 27 has a slot across each side thereof, in each of which slots is a packing strip or plate 28, shown 100 separately in Fig. 6, and having two dowel pins 29. The piston or blade 27 has small bores to receive said dowel pins, as seen in Fig. 7. The piston or blade 27 also has three bores on each side to receive spiral springs 105 30, which bear against the packing strips or plates 28 to keep the same normally spread apart into forcible contact with the guide plates 25, as illustrated in Fig. 7. The piston 27 at each outer edge is slotted longitudi- 110

nally, as seen in Fig. 2 and especially at 31 in Fig. 10. A shoe-bearing strip 32 having an integral rectangular block 33, (Fig. 4) is inserted thereby into said slot. The strip 32 has a longitudinal concave seat 34 and a slot 35 at each end. A shoe or packing strip 36 has an outer, slightly convex, longitudinal surface, shown at 37 in Fig. 10, which conforms to that part of the bore periphery to which it is contiguous, and also has a convex, longitudinal surface, which fits in the concave seat 34 of the shoe-bearing strip 32. There are two of said shoes or packing strips 36, one at each end of the piston or blade 27. 15 Each shoe or packing strip 36 is made in two parts, of which one is tongued, as seen at 38, and one is grooved, as seen at 39, in Fig. 3, the tongue entering the groove. The grooved end has also a socket, in which is mounted a 20 spiral spring 40, one end of the spring pressing against the bottom of the socket, and the opposite end pressing against the end of the tongue. The shoe or packing strip 36 has at each end an integral stud or hub 41 which is 25 semi-circular in cross section. A concentric groove 42 surrounds each hub 41, thus forming a semi-circular annular lip 43 at each end. 30 The piston or blade 27 has on each side four channels 44, two near each outer end. 35 Each channel conducts steam to a tube 45. As seen in Fig. 10, each tube 45 has two internal annular shoulders 46. A ball valve 47 is loosely mounted in each tube 45, and is prevented from leaving said tube by means 40 of the annular shoulders 46. There is a hole 48 through the tube 45 and this is continuous with a bore 49 in the bottom of the slot 31 of the piston or blade 27. There are four friction plates or packings 50, one of which 45 is separately shown in Fig. 5. It is a rectangular block, having its outer end slightly convexed, as shown at 51. It has a semi-circular flange 52 and a concave seat 53. A block 54 projects therefrom, which is concaved on its surface adjacent to the flange 52, thus leaving a semi-circular groove or space 55, in which is received the lip 43 of the packing strip or shoe 36 at each end. On 50 each side edge of the piston or blade 27 there are two springs 56, each secured thereto by screws 57, and whose free ends bear against the friction plates or packings 50, respectively. There are two friction blocks 58, each pressed against the sides of the piston 55 blade 27 by means of spiral springs 59, which are supported in sockets in the adjacent hub 19 of the piston case 18. Each of the friction blocks 58 has a longitudinal groove, as seen in Fig. 11, in which groove one of the friction 60 plates or packings 50 is mounted slidably. A tube or sleeve 60 has a bore to receive loosely each of the hubs 19, and abuts at its outer end the inner flange 61 of the tube or sleeve 17 of each cylinder head 3. A split spring 65 packing ring 62 is mounted on each sleeve 60

and is pressed against the adjacent friction block or packing 50 by a solid ring 63, surrounding the sleeve 60, by means of spiral springs 64, which are seated in sockets in the sleeve 60. The sleeve 60 also has an interior 70 annular flange, by which it is fastened to the end of the hub 19 by screws 65. A bar or keeper 66 is loosely mounted in a slot in the extension 12 and is pressed into constant contact with the piston case 18, by steam, 75 which is conducted to the under side thereof through ports 67 and 68, as illustrated in Figs. 8 and 9. In each of the steam passage ways 10 and 11 there is a block 69 held in abutment with the keeper or bar 66, as represented in said figures. 80

The operation of my improved rotary steam engine is as follows. Beginning this explanation at the time when the piston is in horizontal position, as represented in Fig. 85 8, it is seen that the steam is passing through the ports 15, 8, as indicated by the arrow. The pressure of the steam, as admitted to the cylinder 1, moves the piston from its horizontal position to the vertical position 90 shown in Fig. 9, and thence around in the same direction as indicated by the arrow until the piston comes to a horizontal position again 180° from its first position. During the movement of the piston from said horizontal position to said vertical position the steam power is applied to the piston on an increasing exposure of the piston radially to the piston case; but in moving from the vertical position to the horizontal position 180° 100 from its former horizontal position, the steam power is applied to the piston on a diminishing radial exposure of the piston. The dead steam, which is on the right hand side of the piston, as seen in Fig. 9, is forced 105 out through the exhaust ports, 9, 16. This sliding or reciprocating movement of the piston in the piston case is caused wholly by the eccentrically grooved surfaces of the bore of the cylinder 1, which have a cam like action against the edges of the piston blade 27, as the latter moves progressively along them in continuous but consecutive contact therewith. The oscillating shoes 36 are always 110 in sliding contact with the peripheral surfaces of the bore throughout the entire rotation of the piston case 18, and its shaft. This contact is made steam-tight because of the steam which passes from the cylinder bore through the channels 44 into the tubes 115 45, containing the ball valves 47, and thence through the respective openings 49 into the slots 31, where it presses outwardly the bearing strip 32, in whose concave seats 34 the shoes 36 are placed. The ball 47 is 120 driven by the live steam to the farther end of the tube 45, as shown in Fig. 10. When the engine is reversed, the live steam enters the tube at the right hand end, as seen in 125 said figure and the ball forced in the oppo- 130

site direction, and the piston and associated parts then rotate in the cylinder in the direction opposite to that hereinbefore described. As the piston or blade 27 thus reciprocates, 5 the springs 56 thereof slide upon the friction plates 50, and the friction plates 50 slide upon the friction blocks 58. The friction plates 50 abut the inner surface of the cylinder head 3, as shown in Fig. 2 and slide in the 10 grooves of the friction blocks 58, shown in Fig. 11.

It is evident that a piston and piston cylinder made substantially as hereinbefore specified, are also efficient for a pump and for 15 other similar purposes.

I claim as a novel and useful invention and desire to secure by Letters Patent:—

1. In a rotary steam engine, the combination of a piston case having a central longitudinal slot extending diametrically through it; a shaft on each end of the piston case by which it is rotatably mounted; a piston blade 20 slidably mounted in the slot and provided with two channels on each working end, a cylinder having an eccentrically shaped bore; a strip having a concave longitudinal seat and mounted at each working end of the piston blade in a slot thereof; an oscillating shoe mounted in the concave seat of each of 25 said strips; tubes extending through the piston blade each having interior annular shoulders and communicating with said channels respectively; a ball valve in each tube; and a port from each said tube to the said slots of 30 the piston blade respectively.

2. In a rotary steam engine, the combination of a cylinder having an eccentrically shaped bore; a cylinder head at each of the cylinders; a piston case rotatably mounted 40 by hubs in the cylinder heads and having a central longitudinal slot extending diametrically through it; a piston blade slidably mounted in the slot; four friction plates each in contact with a cylinder head and each hav-

ing a semi-circular bearing with a concave 45 seat and a parallel concave groove; four springs mounted on the ends of the piston blade and each bearing at its free end against one of the friction plates; and an oscillating shoe at each working end of the piston blade 50 and having a semi-circular hub, a semi-circular groove and a semi-circular lip at each end thereof, each of which hubs is mounted in the semi-circular bearing of one of the friction plates, said bearing extending into 55 a semi-circular groove of said oscillating shoe.

3. In a rotary steam engine, the combination of a piston cylinder having a continuously concave bore, all whose chords, intersecting each other in line within the bore located eccentrically to the geometrical axis of said bore, are of the same length; a piston case rotatably mounted lengthwise of said cylinder with its axis concentric with said eccentrically located line; a single piston 60 blade of invariable dimensions mounted slidably in a longitudinal diametrical slot of the piston case and having a longitudinal recess in each of those edges adjacent to the periphery of said bore; a strip mounted loosely 65 in each of said longitudinal recesses, wholly within said piston blade, and provided with a longitudinal concave seat on its outer edge; a semi-cylindrical oscillatory shoe, mounted loosely in each of said strips in the concave 70 seat thereof, and having a convex outer surface adapted to contact with the periphery of said cylinder bore; means for admitting steam pressure against the inner end of the strip in each longitudinal recess of the piston 75 blade.

In testimony whereof I affix my signature in presence of two witnesses.

FRANK J. WATERS.
